(57) **CLAIM**

The ornamental design for a string light, as shown and described.

DESCRIPTION

FIG. 1 is a perspective view of a string light showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the area identified with 8 in FIG. 1;

FIG. 9 is an enlarged view of the area identified with 9 in FIG. 1; and,

FIG. 10 is an enlarged view of the area identified with 10 in FIG. 1.

The regularly spaced broken lines depict portions of the string light and form no part of the claimed design and the dot dash broken lines depict areas of enlargement and form no part of the claimed design. The string light is shown with symbolic break lines in its length. The appearance of any portion of the article between the break lines forms no part of the claimed design.

1 Claim, 10 Drawing Sheets
